(57) **CLAIM**

The ornamental design for a throttle cable adaptor for snowmobiles, as shown and described.

DESCRIPTION

FIG. 1 is an isometric view of one embodiment of a throttle cable adaptor for snowmobiles showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is an isometric view of another embodiment of a throttle cable adaptor for snowmobiles showing my new design;

FIG. 9 is a front elevational view of the embodiment of FIG. 8;

FIG. 10 is a rear elevational view of the embodiment of FIG. 8;

FIG. 11 is a left side elevational view of the embodiment of FIG. 8;

FIG. 12 is a right side elevational view of the embodiment of FIG. 8;

FIG. 13 is a top plan view of the embodiment of FIG. 8; and,

FIG. 14 is a bottom plan view of the embodiment of FIG. 8.

The broken line showing of a fastener in FIGS. 1 and 8 is for illustrative purposes only and forms no part of the claimed design.
